(57) **CLAIM**

I claim the ornamental design for a pendant, as shown and described.

DESCRIPTION

FIG. 1 is a front elevation view of a pendant showing my new design;

FIG. 2 is a rear elevation view thereof;

FIG. 3 is a left side elevation view thereof, the right side being a mirror image thereof;

FIG. 4 is a top perspective view thereof;

FIG. 5 is a second top perspective view thereof;

FIG. 6 is a bottom perspective view thereof; and,

FIG. 7 is a side perspective view thereof.

The broken lines shown in the drawings represent environment and form no part of the claimed design. The broken lines also represent “portions of the pendant which” form no part of the claimed design.
